LAUNDRY NET CLOSURE

William D. Ellis, Atlanta, Ga., and Frederic Thesmar, Memphis, Tenn., assignors to Southern Mills, Incorporated, Atlanta, Ga., a corporation of Georgia

Application March 25, 1943, Serial No. 480,542

2 Claims. (Cl. 150—3)

This invention relates generally to containers in which articles of clothing and the like are laundered and more particularly to improved means for securely closing the open end of such containers.

One method of commercially laundering articles comprises subjecting the articles to laundering operations while contained in open mesh fabric containers or bags. These bags are commonly known as laundry nets, and this term will be employed hereinafter to designate such containers. The primary purpose of this method of laundering is to prevent the clothing of one customer becoming mixed with another and to assure this, the open end of the net must be secured in a manner to withstand the treatment the filled net receives in the laundering operation. To identify them, each filled net is marked by means of a system of legending or numbering which designates the owner of its contents. This legending must be applied to the net so that it will not become detached and preferably so that it is readily visible to facilitate assorting the nets of laundry after washing.

Various methods of closing the open end of the nets have been employed, such as by pinning up with a large safety pin or by gathering in the top of the bag and securing it with a piece of string or cord wrapped and tied around the neck. The pinning method proved relatively satisfactory insofar as it kept the contents of the net intact, however, the life of the net was materially reduced due to the fact that the threads composing the mesh which were engaged by the pin were often pulled and stressed beyond their elastic limit.

Tying, as outlined above, on the other hand, has proved entirely unsatisfactory. In the first place, the neck of the net had to be tied extremely tight in order to maintain the binding cord in place and to prevent the rim of the net from pulling through the binding cord. Then again, after the tied net of clothes had been washed, the binding cord shrank and its knot compacted so tightly it became impossible to remove the binding by any means other than by cutting the cord. However, since the cord had shrunk and become so closely engaged with the net it was difficult, if not impossible, to even cut the cord without also cutting at least some of the threads composing the net.

It is therefore one of the principal objects of the present invention to provide means for tying up the end of a laundry net which will maintain

the net closed during the handling the net receives during the laundering operations.

Another object of the invention is to provide a closure device for laundry nets which may be quickly and easily applied and also quickly and easily removed from the net.

Yet another object is to provide means for closing the open end of laundry nets which substantially equalize strains imposed on the threads comprising the fabric mesh of the net during laundering operations.

A further object is to provide means for binding the gathered-in open end of a laundry net which readily adapts itself to the desired amount of binding necessary for different conditions.

A still further object of the invention is to provide a closure for laundry nets having the above advantages and which is virtually indestructible.

Other objects and advantages will become apparent from the following description and by reference to the accompanying drawing which is employed for the purpose of illustrating a preferred embodiment of the invention.

In the drawing:

Figure 1 is a view in perspective of a filled laundry net about to be closed preparatory to laundering its contents.

Figure 2 is a similar view showing the net with its open end closed in accordance with the concept of this invention.

Figure 3 is a fragmental cross-sectional view taken along the line 3—3 of Figure 2 looking in the direction of the arrows.

Figure 4 is a view in perspective of my closure device illustrating one method of applying the binding cord when securing the gathered-in open end of the laundry net.

Figure 5 is a view similar to Figure 4 but illustrating the opposite side of the plug member.

Figure 6 is a view in perspective, with parts broken away, illustrating a modified method of applying the binding cord when securing the open end of the bag.

Figure 7 is a view in perspective showing the side of the plug opposite that shown in Figure 6.

Figure 8 is a fragmental cross-sectional view taken along the line 8—8 of Figure 5 looking in the direction of the arrows.

Figure 9 is a fragmental longitudinal sectional view taken along the line 9—9 of Figure 4 looking in the direction of the arrows.

Referring in more detail to the drawing, Figure 1 illustrates a filled laundry net which is constructed preferably of an open mesh fabric and comprises a tubular wall, preferably having a

substantially circular bottom 2 secured to the lower end thereof by means of stitching 3, although other means for closing the bottom of the net may be employed. The upper end of the tubular wall 1 is rolled over and bound by suitable means such as overcast stitching to provide a peripheral bead 4 around the edge of the open end 5 of the bag.

The open end 5 of the bag is adapted to be gathered in and secured, as shown in Figure 2, by means of a closure device 6 which is probably best illustrated in Figure 4. In its preferred embodiment, the closure member 6 comprises a plug 7 consisting of a substantially rectangular block of wood or other suitable material having a substantial thickness. In each of the longitudinal edges of the block 7 is provided a cut-out 8 which may be of semi-circular conformation, as illustrated, or other suitable shape, to form a reduced waist or mid-section 9 and flared lower and upper ends 10 and 11, respectively. The block 7 is bored near the upper end 11 to provide an aperture 12 by means of which a loop, designated generally as 13, is attached to the block 7.

The loop 13, preferably composed of strong, flexible fabric tape, is passed through the aperture 12, its ends 15 overlapped and secured together by means of a number of rows of stitching 16. The annulus thus formed is positioned so that this overlapped and stitched portion lies adjacent the aperture 12. The annulus of tape is then flattened, and its opposite sides are secured together by several rows of stitching 17 positioned relatively close to the upper edge 11 of the plug to maintain the overlapped portion in engagement with the aperture. It will be noted that the overlapped and stitched portion of the tape provides a substantial reinforcement to that portion of the loop which will be subjected to friction caused by engagement with the plug.

Suitable indicia, such as numbering 18, is applied to the tape, preferably on the outer surface of both sides of the loop, so that it will be readily visible as shown in Figure 2. This indicia or marking serves to identify the net of laundry as belonging to a specified customer, and, when the net is closed and secured by means of the closure device 6, is affixed to the net in a manner which will prohibit the marking becoming accidentally detached from the net.

To provide an effective but simple means for binding the net closed, which is also easily releasable, I secure one end of a binding cord 19 to the plug member by passing the cord through an aperture 20 provided therefor in one upper corner of the block 7 and then knotting the end of the cord as indicated at 21 to prevent it being withdrawn. A knot 22 is formed in the cord 19 near, but somewhat back from, the free end, while a third knot 23 may be tied in the cord intermediate the first two. The length of the cord and the position of the knots 22 and 23 with respect to its length will be set forth later.

In the opposite upper corner of the block 7 is a socket 24, bored approximately half-way through the thickness of the block, and a slot 25 is formed entirely through the thickness of the block and extends longitudinally from the upper edge of the block to the center of the socket 24. This forms, in effect, a stepped notch for the reception of the knotted free end of the cord 19 to detachably secure this end to the block.

After the articles to be laundered have been

placed in the net, the plug member 6 is first inserted in the open end 5, and the fabric adjacent the open end is gathered together about the plug, preferably with the folds formed by gathering the fabric lying adjacent the flat sides of the plug member. The free end of the cord 19 is next carried over the gathered edge of the bag, passed entirely around the constricted neck below the bead 4, then passed upwardly through the bight thus formed in the cord, brought again over the edge of the net, and inserted in the slot 25 so that the knot 23 engages the socket 24. This operation is clearly illustrated in Figures 4 and 5. The slight tension imparted to the cord by the resiliency of the gathered-in fabric of the net effectively maintains the knot 23 within the socket 24 and prevents the free end of the cord becoming accidentally disengaged from the plug.

As an alternate method of applying the binding cord 19 to the constricted end of the net, which may be used under certain conditions, for instance, with a well-filled or heavy net, the cord may be wound as illustrated in Figures 6 and 7. Here it will be seen that the cord is passed over the upper edge of the net as before, then wound around the constricted neck of the bag twice, the free end brought up and over the edge of the net and inserted in the slot 25 with the knot 22 engaging the socket 24. As stated above, the knot 22 was tied somewhat back from the free end of the cord and by so tying, a loose end or tab 26 is provided by which the operator may grasp the free end of the cord in either attaching or releasing it from the plug member.

The position of these knots 22 and 23 with respect to the secured end of the cord 19 is such that when the cord is passed about the constricted neck of the net and one of the knots engaged with the socket 24, the cord will be drawn sufficiently tight to force the fabric of the net into the notches 8 to securely close the net and maintain the plug member engaged therewith. It is to be noted also that the bead 4 serves to increase the bulk of the fabric at the open end of the bag and thereby prevent the net from being withdrawn through the binding cord 19.

After the nets have been closed, by either one of these methods, they are placed in the laundering apparatus where their contents are washed, rinsed and partially dried. Then the nets, containing cleansed material, are taken to the wet wash assembly of the laundry where they may be suspended on assorting racks by means of the loop 13 for the purpose of separating them according to the indicia 18 carried by the loop.

When the contents are to be removed from the net 1, it is only necessary to grasp the end 26 of the cord and exert a slight pull thereon to release either the knot 22 or 23, as the case may be, from the socket 24, after which the cord may be lifted out of the slot 25 and unwound from the neck of the bag. Thus it will be seen that no untying or cutting of the binding cord is necessary, thereby saving time, labor, and most important of all, preventing injury to the net.

The plug member itself is practically indestructible and, cooperating with a laundry net as above set forth, materially increases the life of the net. Also, the cooperation of the loop 13 with the closure device provides a ready means for handling and identifying the filled nets both before and after the actual laundering operation.

The specific embodiment of my invention herein disclosed and described is for the purpose of illustration only, and many changes may be made

by those skilled in the art such as in its construction, arrangement of parts, size, shape, and so forth, without departing from the spirit of the invention or the scope of the appended claims.

I claim:

1. A closure device for a fabric laundry net, said net having an open end capable of being constricted, comprising a plug member having a reduced mid-section and adapted to be positioned within the open end of the net, a binding cord having one of its ends permanently secured to the plug member, a knot formed in the cord, said cord adapted to be passed about the net, when constricted, to draw the fabric of the net into engagement with the mid-section of the plug member, a slot formed in the plug member for reception of the cord, and a socket cooperating with the slot and adapted to receive said knot thereby to prevent accidental removal of the cord from said slot.

2. A closure device for a fabric laundry net, said net having an open end capable of being constricted comprising a plug member having a reduced mid-section and adapted to be positioned within the open end of the net, a binding cord having one of its ends permanently secured to the plug member, a plurality of knots formed in the cord, said cord adapted to be passed about the net, when constricted, to draw the fabric of the net into engagement with the mid-section of the plug member, a slot formed in the plug member for reception of the cord, and a socket cooperating with the slot and adapted to receive one of said knots thereby to prevent accidental removal of the cord from said slot.
